UNITED STATES PATENT OFFICE.

HENRY H. FREY, OF NEWTON, KANSAS.

HAMMER.

1,067,729.

Specification of Letters Patent.

Patented July 15, 1913.

Application filed August 24, 1912. Serial No. 716,829.

To all whom it may concern:

Be it known that I, HENRY H. FREY, citizen of the United States, residing at Newton, in the county of Harvey and State 5 of Kansas, have invented certain new and useful Improvements in Hammers, of which the following is a specification, reference being had therein to the accompanying drawing.

10 This invention relates to hammer attachments and has special reference to an attachment adapted to be used as a marker or gage. Another object of this invention is the production of an efficient means attached to 15 the hammer for constituting a scraper.

With these and other objects in view this invention consists in certain novel combinations, constructions, and arrangement of parts as will be hereinafter fully described 20 and claimed.

In the accompanying drawings: Figure 1 is a side elevation showing the yoke member in an extended position, and illustrating how the device may be used for extracting nails.

25 Fig. 2 is a side elevation of the device showing the yoke in a closed position and illustrating how the same may be used as a planer or scraper. Fig. 3 is a central longitudinal section of the device. Fig. 4 is a transverse 30 section thereof. Fig. 5 is a perspective of the improved yoke member. Fig. 6 is a bottom plan view of the latching means.

Referring to the accompanying drawings by numerals 1 designates a hammer head 35 which is mounted upon the handle 2 and is provided with the longitudinally extending guiding slots 3. A U-shape yoke member 4 which is provided with the longitudinally extending slot 5 is slidably mounted in the 40 longitudinally extending guiding slots 3 and is prevented from coming entirely out by reason of the screw 6 which fits within the slot 5 when the yoke is mounted upon the hammer head. It will also be seen that the 45

side walls of the yoke member 4 extend divergently toward their inner side as shown at 7 and rest within the converging side walls 8 of the longitudinally extending guiding slots 3 for forming an efficient means to 50

hold the yoke member upon the hammer head. The inner end of the yoke member 4 is provided with the shoulder portions 9 which are engaged by the latching members 10 for holding said yoke member in an extended position when it is desired to use the 55 same as a fulcrum for extracting nails. The

latching member 10 is formed from a blank and is provided with the laterally extending arms 11 and the inwardly extending flange 12. This latching member 10 is pivotally 60 mounted upon the hammer head and is held in position by means of the plates 13, which are welded upon the outer face of the hammer. A coil spring 14 which fits in the receiving socket 15 is positioned upon the 65 inner side of the latching member and normally holds the same in a frictional engagement with the inner side of said U-shape yoke member 4, so that when the yoke member is in an extended position the latching 70 member will rest behind the shoulder 9, and in this manner prevent the yoke member from closing. It will also be seen that the hammer head is provided with an aperture 16, which is adapted to receive the inwardly 75 extending flange 12 when the latching member is compressed to allow the closing of the yoke member 4. It is also obvious that the spring will be held in its correct position by the receiving socket 15 and the inwardly 80 extending flange 12, which prevents the spring from wabbling.

A cutting or scraping lip 17 is formed upon the outer portion of the yoke member 4 and may be used as a planer or scraper by 85 closing the U-shape member 4 and drawing the hammer head across the surface to be planed. A marker or gage 18 is formed upon the opposite side of the U-shape member 4 relative to the scraping lip 17. The 90 inner face of this marker or gage is formed in alinement with the gage formed upon the side of the yoke member as shown at 19, so that if it is desired to make a line about one-half an inch or a similar distance from 95 the edge of the board the gage would be drawn the desired distance from the head of the hammer by aid of the marks formed on the side of the U-shape yoke member.

It will be seen by referring to Figs. 1 and 100 2 that the scraping lip 17 is beveled toward the outer edge and the sides forming an efficient scraper, and it also prevents the hammer from slipping when withdrawing a nail since the edge digs into a support. 105

Having thus described the invention what is claimed as new, is:—

A nail extractor comprising a body portion provided with pawl receiving pockets, pawls pivotally mounted in said pockets and 110 lying flush with the surface of said body portion when in a compressed position, a

fulcrum straddling said body portion and
slidably connected therewith and positioned
to extend across said pawls and cover the
same when moved inwardly, and resilient
means for normally holding said pawls out-
wardly to engage said fulcrum to hold the
same in an extended position.

In testimony whereof I hereunto affix my
signature in presence of two witnesses.

HENRY H. FREY.
